H. C. ETHERIDGE.
ICE CARRIER FOR AUTOMOBILES.
APPLICATION FILED AUG. 8, 1921.

1,431,385.

Patented Oct. 10, 1922.

UNITED STATES PATENT OFFICE.

HARRY CLYDE ETHERIDGE, OF WACO, TEXAS.

ICE CARRIER FOR AUTOMOBILES.

Application filed August 8, 1921. Serial No. 490,598.

To all whom it may concern:

Be it known that I, HARRY C. ETHERIDGE, a citizen of the United States, residing at Waco, in the county of McLennan and State 5 of Texas, have invented certain new and useful Improvements in Ice Carriers for Automobiles, of which the following is a specification, reference being had to the accompanying drawings.

10 This invention relates to ice holders and more particularly to devices of this character for holding ice upon the running board of motor vehicles.

In all of the devices known to the applicant which are on the market at the present time, the ice holders are either permanently secured to the running board and are therefore in the way or they are removably secured and must be stored in the machine in 20 order to be convenient when desired for use.

It is the object of this invention to avoid the difficulties of a permanent ice carrier and also to avoid the necessity of storing a removable ice carrier, and to provide a 25 device which may be readily placed in operative position for holding a cake of ice on a running board or thrown to an out of the way position beneath the running board whereby it is located in an extremely convenient position when desired for use.

Another object of the invention is the provision of a device of this character which is arranged so as to be placed in operative position on top of the running board or thrown 35 to an inoperative position beneath the running board and locked against accidental displacement when in either position.

Further objects of the invention will appear as the following specific description is 40 read in connection with the accompanying drawings which form a part of this application and in which—

Figure 1 is a perspective view of the device shown in operative position on the running board of an automobile, the running board being indicated in section to show the lock casing;

Figure 2 is a bottom plan view with the device in inoperative position;

50 Figure 3 is a detail perspective view showing the position of the notches in the ice carrying member;

Figure 4 is a detail sectional view through the lock casing when the device is in the 55 position shown in Figure 2; and

Figure 5 is a detail sectional view showing

the method of securing a box on the running board of a machine.

Referring more particularly to the drawing, 1 represents the running board of a 60 motor vehicle which has secured beneath the same a lock casing 2, having laterally extending flanges 3 and 4 to receive fastening devices in the way of bolts and screws. The flange 4 is provided with a right angular extension 5 which lies upon the outer longitudinal edge of the running board and which is secured to said edge in any suitable manner. A plate 6 containing any suitable advertising may be secured to the extension 65 5 by the same means that said extension is secured to the front edge of the running board, as will be readily understood.

The lock casing, as shown, is constructed of a single piece of metal with its sides, indicated at 7, provided with rectangular openings 8 for a purpose to be hereinafter described, and provided within the casing on a bolt 9 is a latching member 10 having an extended operating lever 11 by which the 80 operator may release the same from the ice carrying yoke, generally indicated at 12. The bolt 9 has surrounding the same between the latching member 10 and the head of the bolt, a spiral spring which normally 85 tends to hold the latching member in position to engage either of the notches 13 or 14 of the ice carrying yoke, as will be more clearly understood hereafter. The ice carrying yoke is, as shown, substantially J-shaped 90 in outline, consisting of legs 15 and 16, the latter being the longer and having its end rounded as shown at 17, so that when the yoke is fully extended it may be turned within the square or rectangular openings 95 8, as will be readily understood. The end of the leg 16 has secured thereto a stop 18, here shown in the form of a nut threaded upon the end.

The legs 15 and 16 are both rectangular 100 in cross section throughout the major portion of their length and the short leg 15 has its terminal point bent at right angles to form an ice engaging prong 18'. This prong 18', as shown, is pointed at its outer 105 end and threaded throughout the remainder of its length so as to receive a wing nut for a purpose to be hereinafter described. As shown in Figure 2, the leg 16 slides in the openings 8 and the leg 15 slides in rectangular notches 19 formed in the opposite ends of the sides 7 of the casing.

In the operation of the device we will assume that the same is in the position indicated in Figure 2 beneath the running board and with the latch 10 in engagement with the notch 14 of the leg 16. If it is now desired to place the device in operative position for carrying ice the lever 11 is operated to release the latch member from the notch 14 and the yoke drawn outwardly until the stop is brought in contact with the inner side of the casing. In this position the rounded end of the leg 16 will freely turn in the rectangular openings 8 and the yoke member is then turned until the notch 13 is uppermost and the square portion of the leg 16 is in position to enter the rectangular openings 8. The notch 13 is thus placed in a position to be engaged by the latch member 10. The member 12 is then forced inwardly until the latch member engages in the notch 13 when it will be locked against accidental outward movement by the latch member and against turning by reason of the cross sectional configuration of the leg 16 and the shape of the openings 8. In this position the prong 18' is perpendicular to the running board and all that is necessary is to set the cake of ice upon the penetrating prong 18' which enters the ice and holds the same effectually against slippage. When the yoke member is in this position a box, through the bottom of which has been formed an opening to receive the penetrating prong, may be placed on the running board and the thumb nut screwed down on the prong to hold the box in position. When the operator is through with the device, he may raise the lever slightly thus releasing the latch from the notch 13 and by pulling the yoke member as far out as it will come and giving it one-quarter turn thereby aligning the leg 15 with the opening 19 and the notch 14 with the latch member 10. By then forcing it inwardly until the latch engages the notch 14, it will be effectually locked in inoperative position and in this position, as shown, it will be seen that the leg 15 is engaged in the notches 19 so as to prevent the leg 15 from dropping.

What I claim is:

1. In an ice holder for running boards of motor vehicles, a casing secured beneath the running board and having polygonal apertures, a polygonal member slidably fitted in said apertures and having a round-

ed portion adapted to rotate in the apertures, said member having an ice penetrating prong adapted to be positioned on top of the running board or beneath the same, and means for locking the member with the prong in either position. 60

2. An ice holder for the running boards of vehicles including a polygonal member having an extension bent back thereupon in spaced relation thereto and provided at its free end with a spike directed away from the member, a casing secured beneath the running board and having polygonal apertures receiving the member, said member being of greater length than said extension and being provided at the extremity thereof remote from the point at which the extension is attached thereto with a rounded portion adapted to rotate in said apertures, and means for locking the member with the extension thereof above or below the running board, the engagement of said member in said apertures preventing rotation of the member when in the locked 75 position. 75

3. In combination, a casing adapted to be secured to the under surface of the running board of a vehicle, a member directed through the casing substantially J-shaped 85 in form and provided upon the short leg thereof with a spike directed away from the long leg, said member having the long leg thereof shiftable through said casing to move the member to a position with the short leg thereof clearing the edge of the running board, an engagement between the casing and member permitting rotation of the long leg of the member within the casing when the member is in the last named 95 position and preventing rotation of the member when moved inwardly from said position whereby said member may be rotated to swing the prong bearing leg thereof above or below the running board 100 and may be shifted to bring the prong thereof approximately centrally of the running board when in either of said positions, and means for locking the member against movement with relation to the casing when the member is in either of the last named positions and has the prong bearing end disposed approximately centrally of the running board. 105

In testimony whereof I hereunto affix my signature.

HARRY CLYDE ETHERIDGE.
